(No Model.)

J. H. FOSTER.
SPACER OR SPACING GAGE.

No. 548,533.

Patented Oct. 22, 1895.

UNITED STATES PATENT OFFICE.

JAMES HERBERT FOSTER, OF MERIDEN, CONNECTICUT.

SPACER OR SPACING-GAGE.

SPECIFICATION forming part of Letters Patent No. 548,533, dated October 22, 1895.

Application filed June 18, 1895. Serial No. 553,180. (No model.)

To all whom it may concern:

Be it known that I, JAMES HERBERT FOSTER, of Meriden, in the county of New Haven and State of Connecticut, have invented a new and Improved Spacer or Spacing-Gage, of which the following is a full, clear, and exact description.

The invention relates to hand-printing with ready-made characters, and its object is to provide a new and improved spacer or spacing-gage which is simple and durable in construction and arranged to enable the operator to place the printing characters in the proper position to form accurately spaced and aligned words.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a plan view of the improvement as applied and arranged for printing in a straight line. Fig. 2 is a transverse section of the same on the line 2 2 of Fig. 1. Fig. 3 is a plan view of the improvement arranged for printing characters in the segment of a circle, and Fig. 4 is a sectional side elevation of the same on the line 4 4 of Fig. 3.

The improved gage is provided with a rule A, on which is fitted to slide longitudinally the rest B, formed with a transversely-extending arm B', on which rests one side of the printing-block C, provided on its under side with a character. The front end of this block C abuts against the side of the rule A, so that the block is held firmly in position and consequently guided by the rule A and arm B' while printing.

In the rear of the extension-arm B' is arranged a spacer-arm D', parallel to the arm B' and formed on the gage D, held adjustably on the rest B and adapted to be secured thereto by a clamping-screw E. The latter is held in the rest B and extends through the longitudinal slots B² and D², formed in the rest B and gage D, respectively. The lower head of the clamping-screw E is fitted to slide loosely in a longitudinally-extending recess A', formed

in the top of the rule A. Now it will be seen that by loosening the clamping-screw E the rest B and the gage D may be adjusted one on the other, so as to bring the two arms B' 55 and D' a distance apart corresponding to the space desired between two characters printed on the paper or other article.

When the rest B and gage D have been adjusted, they are fastened together by the 60 clamping-screw E, and then the operator places the printing-block C in position on the arm B', as previously described, and illustrated in Fig. 1, with the other arm D' on one side of the character previously printed. 65 When this new letter has been printed, the block C is removed and the rest B and gage D are shifted forward on the rule A to bring the arm D' again to one side of the previously-printed letter, so that a new type-block can 70 be placed on the arm B' and rule A to print the next following character. This operation is repeated until the entire word is formed.

It will be seen that by the arrangement described the characters are first brought into 75 proper alignment and at the same time are accurately spaced, so as to insure proper printing.

When it is desired to print words in the segment of a circle, as shown in Figs. 3 and 4, 80 I provide the rule A² with a series of apertures A³, arranged longitudinally at or near the middle of the rule, one of the apertures being adapted to be engaged at a time by a pointed tool F in the form of an awl or like 85 instrument. This tool F is passed through one of the apertures A³ into the paper or board on which the word is to be printed to serve as a fulcrum for the rule A². On the upper or outer end of this rule A² is held the rest 90 B³, having, besides the slot B⁴ and arm B⁵, an auxiliary arm B⁶, the gage D³ having the arm D⁴ arranged crosswise, so that the arm D⁴ stands parallel to the auxiliary arm B⁶. The gage D³ is adjusted transversely on the 95 rest B³ to bring the arms B⁶ and D⁴ the desired distance apart, and then the rule A² is swung from the tool F, as a pivot after a character has been printed. It is understood that the character-block is placed on the arm 100 B⁶, with the other arm D⁴ on one side of the previously-printed character. A clamping-

screw E' serves to fasten the rest B³ and gage D³ together, and the head of this screw E' is adapted to pass into a recess A⁴, leading from the longitudinal recess A⁵ of the rule. (See Figs. 1 and 4.)

The slots B⁴ and D⁵ in the rest and gage, respectively, are enlarged at the end to permit of passing the screw E' into the side recess A⁴. On the under side of the rule A² is placed a washer G, around the pointed end of the tool F, so that the rule A² is held a suitable distance above the paper, board, or other article on which the characters are printed. A similar washer G', of rubber, felt, or like material, is attached to the under side of the rule A² at the other end.

Having thus fully described my invention, I claim as new and desire to secure by Letters Patent—

20 1. A spacing gage, comprising a rest provided with an arm extending therefrom, and a gage adjustable on the rest and provided with an arm extending parallel to the arm of the rest, substantially as shown and described.

25 2. A spacing gage, comprising a rule, a rest adjustable thereon and provided with a projecting arm, and a gage adjustable on the rest and provided with an arm extending parallel

to the arm of the rest, substantially as described. 30

3. A spacing gage, comprising a rest provided with two projecting arms standing approximately at right angles to one another, and a gage adjustable upon the rest and provided with an arm arranged to extend parallel to either of the arms of the rest, substantially as described. 35

4. A spacing gage, comprising a rest provided with two projecting arms arranged at an angle to each other, and a gage adjustable upon the rest and provided with an arm arranged to extend parallel to either of the arms of the rest, substantially as described. 40

5. A spacing gage, comprising a rule, a rest adjustable longitudinally thereof and provided with two projecting arms, one of which extends longitudinally of the rule and the other transversely thereof, and a gage adjustable on the rest and provided with an arm arranged to extend parallel to either of the arms of the rest, substantially as described. 45 50

JAMES HERBERT FOSTER.
